(57) **CLAIM**

The ornamental design for a bib for a fuel dispenser nozzle and fuel tank inlet conduit, as shown and described.

DESCRIPTION

FIG. 1 illustrates a front left-side perspective view of a bib for a fuel dispenser nozzle and fuel tank inlet conduit; FIG. 2 illustrates a front view thereof; FIG. 3 illustrates a rear view thereof; FIG. 4 illustrates a left-side view thereof; FIG. 5 illustrates a front view thereof; FIG. 6 illustrates a top view thereof; FIG. 7 illustrates a bottom view thereof; FIG. 8 illustrates a perspective view thereof, showing the bib installed on the fuel dispenser nozzle; and, FIG. 9 illustrates a perspective view thereof, showing the bib installed on the fuel tank inlet conduit of a vehicle. The broken line showing of portions of the fuel dispenser nozzle in FIG. 8 and the vehicle in FIG. 9 are for the purpose of illustrating environmental structure and form no part of the claimed design.
